UNITED STATES PATENT OFFICE.

CHARLES E. McDOWELL AND HORACE G. STRIPE, OF NEW YORK, N. Y.;
SAID McDOWELL ASSIGNOR TO JUDSON LAWSON & SON, OF SAME PLACE.

DESIGN FOR A NEWSPAPER-STAND.

SPECIFICATION forming part of Design No. 33,760, dated December 18, 1900.

Application filed November 20, 1900. Serial No. 37,179. Term of patent 14 years.

To all whom it may concern:

Be it known that we, CHARLES E. McDOWELL and HORACE G. STRIPE, citizens of the United States, residing at New York, in the county and State of New York, have invented and produced a new and original Design for a Newspaper-Stand, of which the following is a specification, reference being had to the accompanying drawings, forming part thereof.

As shown in the drawings, the leading or material features of our design consist of a cabinet rectangular in shape in cross-section, (indicated by reference-numeral 5,) tables 6 and 7 on two of the opposite sides, and braces 8 and 9.

Surmounting the cabinet is a skeleton frame comprising columns 10, supporting a polygonal cover 11 and resting on a similarly-shaped platform 12, which is mounted on a rectangular platform 13. Further features 25 of the skeleton frame are the plurality of rods 14, radially mounted in line with the respective columns 10, and the rectangular-shaped wire frames 15, having coils 16 at the upper and lower ends of each, which surround spin- 30 dles 17. A shaft 18 passes up through the said skeleton frame and projects above the same and carries four radially-mounted frames 19 in the same plane, a frame 20 above the frames 19, and at the top the grille 21. 35

Having described our invention, what we claim as new, and desire to secure by Letters Patent, is—

The design for a newspaper-stand, as herein shown and described. 40

In testimony whereof we have signed our names to this specification in the presence of two subscribing witnesses.

CHARLES E. McDOWELL.
HORACE G. STRIPE.
